UNITED STATES PATENT OFFICE.

ANDREW J. SANFORD, OF NEWARK, OHIO.

DESIGN FOR A BOWL OR NAPPY.

44,939.

Specification for Design.

Patented Nov. 25, 1913.

Application filed October 8, 1913. Serial No. 794,177. Term of patent 14 years.

To all whom it may concern:

Be it known that I, ANDREW JOHN SANFORD, a citizen of the United States, residing at Newark, Ohio, have invented a new, original, and ornamental Design for a Bowl or Nappy, of which the following is a specification, reference being had to the accompanying drawing, forming part thereof.

Figure 1 is a side elevation of a bowl or nappy embodying my design, and Fig. 2 is a bottom plan of the same.

I claim:

The ornamental design for a bowl or nappy, as shown.

ANDREW J. SANFORD.

Witnesses:

MAX B. NORPELL,
ETHEL EVANS.
